UNITED STATES PATENT OFFICE

DAVID E. HUNTER, OF MUSKEGON, MICHIGAN, ASSIGNOR TO SHAW-WALKER COMPANY, OF MUSKEGON, MICHIGAN, A CORPORATION OF MICHIGAN

VERTICAL FILING CABINET

Application filed August 13, 1927. Serial No. 212,785.

This invention relates to improvements in vertical filing cabinets and consists of the matters hereinafter described and more particularly pointed out in the appended claims.

5 The invention has to do more especially with receptacles or drawers of cabinets or cabinet units used in what is commonly known as the vertical system of filing. In such system the papers or records are filed 10 on edge in the receptacle or drawer in their proper positions determined by suitable guide or index cards and are intended to be retained in vertical position, whence the name. It has been found, however, that in the operation 15 of such systems with the receptacles or drawers as heretofore constructed, the papers or records generally stand in anything but a vertical position.

Heretofore file receptacles of the kind have 20 consisted of a box-like container, drawer or tray having a follower plate mounted to slide lengthwise of the filing space and adapted to be clamped in any desired position therein to accommodate variable quantities 25 of file contents. In some cases the drawer is provided with a guide rod extending lengthwise of the filing space and set into a groove in its bottom wall and the guide or index cards are anchored to the rod by perforated ears engaged thereon.

Such receptacles are subject to several objections: (1) The adjustment mechanism for the follower plate is apt to get out of order and fail to catch and hold in the adjusted position with the result that valuable time is often lost in manipulating said followers. (2) When a receptacle containing a normal volume of records or cards is pushed with normal force into the cabinet 40 or case, the sudden stop of the receptacle causes the records or cards to slide rearwardly against the follower plate due to the momentum of said records or cards. This produces (a) uneven pressure conditions in 45 the file; (b) uneven spacing of the file and contents; and (c) a crowding action which tends to raise the contents from the normal seat on the bottom of the receptacle with the resultant loss of time for readjusting the 50 contents to their normal position. (3) A

considerable loss of filing space on account of the space required for the follower plate mechanism. (4) In cases where the guide rods are used which tend to prevent the mass raising above referred to, there is the still 55 greater loss of space required for the guide rod mechanism.

The object of my invention is to produce a receptacle or drawer adapted for a vertical system of filing in which the above objections and faults are eliminated and in which the file contents are at all times held in convenient substantially vertical reference position so that the records may be quickly examined in the file or readily and easily 60 withdrawn therefrom either singly or in groups with or without their index cards, with a resultant saving in time and labor as compared to that involved in the use of former receptacles for the purpose. 70

Another object of my invention is to produce a filing receptacle of the kind in which the space heretofore required for the follower plate mechanism and the guide rod is eliminated, thereby saving vertical space 75 which in the aggregate of a number of filing units placed one upon the other, will amount to enough to substantially increase the number of filing units that may be placed in the limited vertical space generally permissible 80 for cabinets of the kind. With floor space rapidly increasing in cost, this is a material advantage of the invention.

These and other advantages of the invention will appear more fully as I proceed with my specification.

In the drawings:—

Figure 1 is a perspective view of a cabinet containing five of my improved drawers, one of the drawers being shown withdrawn partly 90 from the stack.

Figure 2 is a longitudinal section through one of the drawers.

Figure 3 is a transverse section through one of the drawers.

Figure 4 is a top plan view of the same.

Figures 5, 6 and 7 are detailed views to be described more particularly later in the specification.

In illustrating and describing my inven- 100

tion I have shown it as applied to a cabinet made up of a plurality of vertically stacked units, each consisting of a housing or body and of the novel drawer or receptacle itself.

5 Referring now to that embodiment of the invention illustrated in the drawings:—10 indicates the cabinet, including, as shown, five cabinet units each including a drawer 11. The units including the housing or body 10^a 10 and the drawers with their guide rails and the like for slideably supporting them within their housings, are and may be of any familiar sheet metal construction, the details in this respect having no part in the invention. 15 12 indicates the bottom wall of the drawer; 13, 13, its side walls; 14 indicates the rear end wall of the drawer, and 15 indicates the upright front wall of the drawer which closes the opening into the body or housing 10^a in 20 the usual manner. The side walls of the drawer have rails 16 by means of which they are supported on co-related rails (not shown) within the housing or body 10^a.

The bottom wall 12 of the drawer is flat 25 and the usual follower plate is omitted. Within the drawer there are provided a plurality of transverse division members or buttress plates which are located at horizontally spaced, preferably equal intervals between 30 the front wall 15 and the rear wall 14 of the drawer. Said division members or buttress plates are so mounted and anchored within the drawer as to be capable of a limited swinging movement to either side of a transverse 35 vertical plane, but are anchored against vertical withdrawal from the drawer. The buttress plates are of substantially the same depth as the side walls 13 of the drawer and are mounted with their bottom edges in such 40 close proximity to the bottom wall 12 of the drawer that the cards, record sheets or other filing contents of the drawer may not slide through the space between said bottom edge and the bottom wall of the drawer.

45 Any suitable means may be adopted for mounting the division members or buttress plates 17 within the drawer in the manner described. As shown herein and preferably, each plate is provided at or near its bottom 50 edge with laterally extending flat lugs 18, 18 which are engaged loosely in vertical slots formed in longitudinally extending strips 20 attached to the side walls of the drawer at the bottom and running lengthwise of said 55 walls. Said lugs may be formed in any one of a number of ways but where the plates 17 are made of light sheet metal as shown in the drawings, they are preferably stamped and formed from separate plates of sheet-metal. 60 As illustrated said plates comprise leaf sections 21, 21 with a connecting strip 22 of such form that when the plate as a whole is bent upon itself, the connecting strip forms a flat lug 18 of double thickness and the leaf sections 21 form attaching members between 65

which the plate 17 may be engaged and by means of which the lug may be attached to said plate, preferably by spot welding.

The strips 20 containing the slots 19 are also made of sheet metal and are formed with side flanges and with offset flanges 24 at their ends by means of which they may be attached to the side walls 13 of the drawer in such offset relation from the plane of said side wall as to give room for the ends of the lugs 18 which extend through the slots 19. 75

The method of assembly of the buttress plates or division members in the drawer will manifestly depend upon the rigidity and thickness of the metal used. In case of the light sheet-metal plates described, the strips 20 may be attached in place and the lugs thereafter may be sprung into position through their respective slots 19 by flexing the plates as illustrated at 17^x in Figure 4. In case of more rigid plates, other obvious methods of assembly would be used. In any case the construction must be such that the plates, as hereinbefore pointed out are anchored in the drawer and are non-removable. 80 Where the lugs 18 are provided by separate strips, as shown herein, the buttress plates are preferably "bumped" or otherwise deformed to present rounded projections 25 on opposite sides of the plate above the shoulders 26 formed by the upper edges of the attaching members 21. These rounded projections prevent the bottom edges of the file contents, folders, cards, sheets or the like, from engagement with and arrest by said shoulders 26. 85

The buttress plates 17 divide the drawer longitudinally into a plurality of filing sections each more or less independent of all the other filing sections. In these comparatively small filing sections there is no danger of an occurrence of uneven pressure conditions or uneven spacing or of a crowding action tending to raise the file contents from their normal seat on the bottom of the drawer. 90 The file contents between each pair of buttress plates are never crowded and by shifting the contents of a division forward of the particular file which is to be examined or removed, this being made possible by the 95 swinging feature of the buttress plates, ready access to the particular files to be examined or the like may be had in the comparatively small space between the buttress members. There is no possibility for any sliding or slipping action of the files tending to throw them into a non-vertical position. As there is no abutment plate to adjust or to manipulate in order to loosen the pressure on the 100 files, there is a great saving of time when any file in the drawer is to be referred to, removed or examined, since manifestly a simple pressure of the finger or hand will swing those files together with the buttress plates 105 110 115 120 125 130

which are forward of the particular file to be examined, back out of the way.

It is thought that the operation and advantages of the invention will be fully apparent to those familiar with the art from the foregoing description.

While in illustrating and describing the invention I have referred to many specific details of mechanical construction and arrangement of parts, it is to be understood that the invention is in no way limited thereto except as may be pointed out in the appended claims.

I claim as my invention:

1. A receptacle for vertical filing, comprising a drawer having a bottom and side walls, a plurality of buttress plates extending transversely of said drawer, said buttress plates dividing said drawer into a plurality of compartments, each plate being provided with laterally extending flat lugs near its bottom edge, and means providing narrow, vertical slots at the sides of the drawer near the bottom, in which slots said lugs are engaged and have limited movement.

2. A drawer for vertically filing, having a bottom and side walls, a plurality of buttress plates extending transversely of said drawer and spaced longitudinally thereof, each plate being provided with laterally extending flat lugs near its bottom edge, and longitudinal strips fixed to the sides of the drawer at the bottom and containing flat narrow slots in which said lugs are engaged.

In testimony that I claim the foregoing as my invention, I affix my signature this 10th day of August, A. D. 1927.

DAVID E. HUNTER.
